UNITED STATES PATENT OFFICE.

ARNOLD HENRY BONGERS, OF LONDON, ENGLAND, ASSIGNOR OF ONE-HALF TO GASTON BOUDOU, OF LONDON, ENGLAND.

HEATER FOR PERMANENT HAIR WAVING.

Application filed March 22, 1924, Serial No. 701,154. Renewed December 5, 1925.

To all whom it may concern:

Be it known that I, ARNOLD HENRY BONGERS, a subject of the King of Great Britain, of 7 The Exchange, Muswell Hill, London, 5 N. 10, England, have invented new and useful Improvements in Heaters for Permanent Hair Waving; and I do hereby declare the following to be a full, clear, and exact description of the same.

10 The present invention relates to permanent hair waving appliances, and refers more particularly to those such appliances which are employed for applying heat to a strand of hair coiled upon a curler, so as to impart permanency to the wave. Such appliances commonly comprise a tubular chamber adapted to receive a curler with the hair wound thereon and one or more heating devices, generally electrical, associated with 15 the outside of the tube.

The present invention has for its object to improve the action of such heating appliances, firstly by causing the heat to be applied more particularly to the portion of the 20 hair nearest the root and secondly by enabling the heat to be applied either to the root portion only or more or less uniformly to the whole of the hair under treatment.

The appliance according to the invention 25 comprises a metallic tubular member to receive a coiled strand of hair, a cylindrical heating device around and spaced from one end portion of the tubular member, and a metallic ring or sleeve disposed and establishing heat conductive communication between the end portions only of the heating device and tubular member. In the construction hereinafter described by way of example, an adjustable device is provided 30 for establishing heat conductive communication at will between the other end portion of the heating device and the portion of the tubular member projecting through the heating device. Preferably such adjustable device consists of a tube or sleeve slidable on 35 the tubular member so that one end thereof can enter or withdraw from the space between the heating device and the tubular member at will.

40 In order that my invention may be clearly understood and more readily carried into practice, I have appended hereto one sheet of drawings illustrating the same, where in:

45 Figure 1 is a perspective view of one

construction of appliance according to the invention,

Figure 2 is a sectional elevation of the appliance,

Figures 3, 4, 5 and 6 are views of disassembled parts, and

Figure 7 is an end view of the parts shown in Figures 4 and 6 assembled.

The tubular heating chamber 1, which is made of aluminium or other suitable metal, 55 may be open, but as shown is closed at one end by a plug 2 having a hole to permit the escape of moisture, and is flanged at the other end, a recess 3 being pressed up in the periphery of the end of the tube to 60 permit the passage of the hair into the tube 1. Upon the open end of the tube 1 is arranged an electrical heating device consisting of an outer cover 10 and a ring 9 of heat insulating material, an inner metal tube 75 5 covered with a layer of insulating material such as mica, and a winding of resistance wire 8 covered by a layer of asbestos 7. The tube 5 is fitted in the ring 9 and is spaced from the wall of the chamber 1 80 by a ring 11 of aluminium or other metal arranged round the tube 1 near the end thereof. This ring 11 serves to conduct the heat of the winding 8 from the tube 5 to the end portion of the chamber 1, practically no heat being normally transferred in any other manner from the tube 5 to the chamber 1.

Slidable upon the portion of the tube 1 90 projecting from the heating device is a metal tube 12 fitting snugly on the tube 1 and fitted into a sleeve 13 of heat insulating material. The tube 12 may be split longitudinally as shown at 14 (Figure 3) and is slotted near its free end at 15. 95 Screws 16 pass through the cover 10, ring 9, and slots 15, and serve not only to limit movement of the tube 12, but also to clamp the heating device into position.

If it is desired, as in re-waving hair, 100 only to heat the hair near the roots the tube 12 is pulled to the left (Figure 2) so as to be clear of the tube 5, but if it is desired, as in waving straight hair, to heat the hair more or less uniformly throughout its 105 length, the tube 12 is moved to the right, when it engages in the end of the tube 5 and then forms another path for the heat to pass from the tube 5 to the tube 1. The action of the tube 12 is similar to the ring 110

11, but the heat conducted thereby is distributed over a longer length of the chamber 1 so that the greatest heat is still obtained where required near the roots of the hair.

5 The open end of the chamber 1 may be fitted with any kind of closure adapted to allow passage of the hair into the chamber 1, but preferably a movable rubber faced cover 17 pivoted between links 18 and operated by a bridge piece 19.

10 Preferably a small piece 20 of sheet cork or other heat insulating material is inserted into the end portion of the cover 10, behind the recessed portion 3 of the tube 1, 15 so as to prevent that portion of the tube 1 from collecting heat from the end of the heater tube 5 and thereby becoming hot enough to burn the hand should it come into contact with the recessed portion 3 or any

20 other part of the edge of the tube 1.

What I claim is:—

1. An appliance of the kind set forth, comprising a metallic tubular hair receiving chamber, a tubular heating device surrounding and spaced from said chamber throughout its length, a metallic sleeve interposed between said heating device and said chamber so as to provide one path for the transfer of heat from the former to the latter, 25 and adjustable means comprising a metallic member adapted to be moved to control a second path for the transfer of heat from the heating device to said chamber.

2. An appliance of the kind set forth, 30 comprising a metallic tubular hair receiving chamber, a heating device surrounding and spaced from one end portion of said chamber, a metallic ring disposed between the end portions only of the heating device and tubular member, and an adjustable member adapted to be interposed between and to contact with the opposite end portion of the heating device and the portion of the tubular chamber projecting therethrough, so as 40 to permit the conduction of heat from the heater to an intermediate part of the chamber.

3. An appliance of the kind set forth, 45 comprising a metallic tubular hair receiving chamber, a heating device surrounding and spaced from one end portion of said chamber, a metallic ring disposed between the end portions only of the heating device and tubular member, and a metallic sleeve slidable externally, along said chamber into and out of a position in which one end thereof engages, and provides heat conductive connec-

tion between the medial portion of the chamber and an end portion of the heating device.

60

4. An appliance of the kind set forth, comprising a metallic tubular hair receiving chamber, a heating device surrounding and spaced from one end portion of said chamber, a metallic ring disposed between the end portions only of the heating device and tubular member, a metallic sleeve slidable externally along said chamber into and out of a position in which one end thereof engages, and provides heat conductive connection between the medial portion of the chamber and an end portion of the heating device, and a pin and slot connection between the sleeve and the heating device to limit sliding movement of the sleeve on the 75 tubular member.

70

5. An appliance of the kind set forth, comprising a metallic tubular hair receiving chamber, a heating device surrounding and spaced from one end portion of said chamber, a metallic ring disposed between the end portions only of the heating device and tubular member, a metallic sleeve slidable externally along said chamber into and out of a position in which one end thereof engages, and provides heat conductive connection between the medial portion of the chamber and an end portion of the heating device, a pin and slot connection between the sleeve and the heating device to limit 80 sliding movement of the sleeve on the tubular member, and a sleeve of heat insulating material secured to said metallic sleeve.

85

6. An appliance of the kind set forth, comprising a metallic tubular hair receiving chamber, a heating device therefor, and means, including fixed means and adjustable mechanical means, adapted to apply the heat of said device to one end portion of said chamber in one position of adjustment 95 of the adjustable means, and to both end portions of said chamber in another position of adjustment of said adjustable means.

90

7. An appliance of the kind set forth, comprising a metallic tubular hair receiving chamber, a heating device therefor, and mechanical means including a fixed member and an adjustable member adapted for conducting heat from the heating device by separate paths to different portions of the 100 length of said chamber.

105

In testimony whereof I affix my signature.

ARNOLD HENRY BONGERS.
